DOORBOLT FOR MULTILEAF DOORS

Maurice Vincent, Paris, France

Application August 22, 1932, Serial No. 629,975,
and in France August 4, 1932

2 Claims. (Cl. 292—145)

For locking apartment doors having several leaves, use is made of bolts of the so-called "needle" type which are adapted to hold, at will, one or more of these leaves stationary, and the 5 bolts of which are constituted by rods housed, near the rabbet of the leaf, in a recess provided therein, so as to be completely hidden.

The placing of these needle bolts on the doors is very difficult, and can be effected only by 10 skilled workmen. Moreover, when, in the case of a door having three or four leaves for instance, a leaf provided with such bolts carries a second leaf pivoted on its rabbet, the pin hinges serving for the assemblage are secured on the 15 first leaf, independently of the bolt, so that the manufacture of the iron fittings is very complicated and costly.

The present invention has for its object improvements in iron fittings comprising locking 20 bolts of this kind, for the purpose, in particular, of considerably simplifying the manufacture of the same and especially the placing in position, which latter can be effected, for a bolt and a pin hinge mounted on one and the same rabbet, 25 in a single operation and by unskilled labour.

According to the invention, the locking bolt, instead of being mounted within a housing or recess provided in the thickness of the wood, is fitted in a groove provided in the rabbet, and 30 exactly fills up the said groove, so that it is as completely concealed as an ordinary needle bolt, although the formation of its housing or recess and its fixing within the latter are much more easy.

35 In a particular arrangement according to the invention, when a second leaf is hinged on the rabbet of a leaf provided with a bolt of this kind, each hinge plate for constituting the pin hinge is rigid with the plate of the bolt, so that 40 the placing in position of the bolt and of the adjacent pin hinge plate are effected in a single operation, as simple as the placing of an ordinary pin hinge.

45 A form of carrying out the subject-matter of the invention will be described hereinafter, by way of example only, with reference to the accompanying drawings, in which:

Fig. 1 is a partial elevation, with parts broken away, of leaves provided with the improved locking bolt.

Fig. 2 is a plan view, partly in section, and on an enlarged scale, of the said leaves.

55 Fig. 3 is an elevation of a bolt provided with a pin hinge.

Fig. 4 is a similar view of a bolt alone devised in a slightly different manner.

In this example, it will be assumed that a door provided with three or four leaves is under consideration, this door having, on one side, two 60 leaves V, V₁, and, on the other side, one or two leaves (not shown).

The leaf V is mounted on the door frame D in the usual manner, by means of pin hinges 1. It carries the leaf V₁, hinged on its rabbet F, and 65 can be held stationary at will, in closed position by two locking bolts, which, according to the invention are devised as follows:

The inner portion of the rabbet F is provided, at each of its ends, with a groove R in which 70 the bolt is received (in the drawings, the upper bolts alone have been shown; the lower bolts are, as usual, symmetrically arranged, at the bottom of the door).

This bolt is carried by a plate or upright 2, 75 constituted by a flat iron member fitted in the rabbet, on the edges of the groove R, so as to completely conceal the device.

The upper portion of this plate forms a right- 80 angular projection 2a which is embedded in the top of the leaf V, and the plate is secured by means of screws 3.

On the inner face of the plate 2, within the groove R, are secured guides 4, preferably of copper, for reducing friction and avoiding wedging due to oxidation, in which guides 4 the locking bolt or rod 5 slides.

The upper end of this bolt or rod 5 passes through a mortice 2b provided in the projection 85 2a and fits, in closed position, in a staple 6 carried by the upper door frame member D₁ (see the portion in dot and dash lines in Fig. 1).

Its lower end 5a is bent at 90° towards the plate 2 and passes through a mortice 2c provided in this plate, so that access may readily be had 95 thereto when the leaf V₁ is open and that the locking bolt may be operated. It does not appreciably project beyond the plate 2 so as not to hinder the folding of the leaf V₁.

The bolt 5 also forms (Fig. 3) heel pieces or 100 shoulders 5b which, abutting against the guides 4, limit its upward and downward movements, and it is provided with recesses 5c through which can pass the screws securing the plate 2.

A leaf spring 8, arranged between the plate 105 and the bolt 5, presses the latter against the guides and prevents play from taking place.

The leaves V and V₁ are assembled by means of pin hinges, and, according to a particular arrangement of the invention, the half pin hinges 110

corresponding to the leaf V are not directly secured to the latter, but on the plates carrying the locking bolts.

The drawings show in particular, at the level 5 of the upper bolt, a pin hinge one half 7a of which corresponding to the leaf V is rigid with the plate 2, the other half, 7b being secured in the usual way on the inner face of the rabbet F₁ of the leaf V₁.

10 The placing in position of the bolts and of the half pin hinges 7a is thus effected in a single operation, quite as simply as for the half pin hinges alone in the ordinary devices.

15 At the end of the leaf V₁ is mounted a locking device identical to the preceding one, but without the half pin hinge 7a.

Besides the advantages above mentioned, this bolt is also of remarkably rugged construction.

20 Fig. 4 illustrates a modification according to which, instead of recesses 5c, mortices 5d are provided in the sliding bolt 5 for the passage 25 of the fastening screws. This arrangement assumed to be applied to a locking bolt only, is, of course, also applicable to a locking bolt provided with a half pin hinge of the type illustrated in Fig. 3.

It is to be understood that it is possible to 30 modify in any suitable manner the shape, arrangement and method of assemblage of this improved locking bolt, according to the condi-

tions of manufacture, the shape and the arrangement of the leaves for which it is intended, without departing thereby from the scope of the invention. Any suitable tools and methods can also be provided for the manufacture of this locking bolt, particularly, by moulding, pressing, etc.

I claim:—

1. The combination of a vertical locking bolt 80 for door leaves, adapted to be fitted in a groove provided in the rabbet of the door leaf, a plate adapted to be secured on the same rabbet of said door leaf, means on the rear face of this plate for guiding said locking bolt in the vertical direction and a pin-socket on one longitudinal side of said plate and in one piece with the latter.

85 2. The combination of a vertical locking bolt for door leaves, adapted to be fitted in a groove provided in a rabbet of the door leaf, a plate adapted to be secured on the same rabbet of said door leaf, means on the rear face of this plate for guiding said locking bolt in the vertical direction, a pin-socket on one longitudinal side of 90 said plate and in one piece with the latter, a separate pin-socket adapted to pivot on the first 100 pin-socket, a securing plate in one piece with said separate pin-socket and provided for securing said separate pin-socket to another door leaf.
